UNITED STATES PATENT OFFICE.

L. D. SPRATT, OF CHICAGO, ILLINOIS, ASSIGNOR OF ONE-HALF TO CHARLES SCHLOTFELDT, OF CHICAGO, ILLINOIS.

RAILROAD TIE.

Application filed April 10, 1922. Serial No. 550,966.

To all whom it may concern:

Be it known that I, L. D. SPRATT, a citizen of the United States, residing at Chicago, in the county of Cook and State of Illinois, have invented certain new and useful Improvements in Railroad Ties, of which the following is a description.

My invention relates to improvements in railroad ties, and more particularly to metallic ties adapted to be substituted for the wooden ties usually employed. One of the objects of my invention is to provide means cooperating with my metallic tie for resiliently supporting the load to permit the vertical movement of the rail, as is provided by the inherent resiliency of wooden ties. Another object of my invention is to provide a hollow metallic tie having a flanged cover thereon, whereby water or the like is prevented from working its way into the hollow interior of the tie. Another object of my invention is to provide means for preventing the spreading of the rails on the tie, said means being part of the tie itself. Another object of my invention is to provide means for removably securing the cover to the main portion of the tie in such a way that said securing means will be prevented from accidentally coming off. The invention has among its other objects the production of a device of the kind described which is simple, compact, durable, reliable efficient and satisfactory for use wherever found applicable. Many other objects and advantages of the construction herein shown and described will be obvious to those skilled in the art from the disclosure herein given.

To this end, my invention consists in the novel construction, arrangement and combination of parts herein shown and described, and more particularly pointed out in the claims.

In the drawings, wherein like reference characters indicate like or corresponding parts,

Fig. 1 is a top plan view of a pair of rails supported by my improved ties;

Fig. 2 is a section taken substantially on line 2—2 of Fig. 1;

Fig. 3 is a section taken substantially on line 3—3 of Fig. 2;

Fig. 4 is a section taken substantially on line 4—4 of Fig. 2;

Fig. 5 is a section taken substantially on line 5—5 of Fig. 1;

Fig. 6 is a section taken substantially on line 6—6 of Fig. 2;

Fig. 7 is a sectional detail of the means used for securing the cover to the hollow tie; and

Fig. 8 is a detail of a sleeve used in connection with the securing means shown in Fig. 7.

In the drawings wherein I have illustrated the preferred embodiment of my invention, there is shown a pair of rails 1 of any suitable size or shape, said rails having a flanged base 2. The ties each comprise a hollow box structure 3 which is preferably of elongated shape, as is ordinarily used or found satisfactory for ties, and may be made in one or more parts as desired. The material used in making the tie may be such as desired and is preferably metallic. A cover 4 is adapted to close the open or top side of the box structure 3, said cover having its side edges flanged at right angles thereto, as at 5, so as to slidably engage the vertical walls of the box 3, and thus prevent any liquids from working their way in between the cover and box. At points intermediate of the length of the box, there are provided transverse partitions or reinforcing webs 6, whereby compartments 7 are formed in the box.

Carried by the box and projecting into each of the compartments 7, are one or more pins 8 adapted to receive the coil springs 9 thereon and form guides therefor. The free ends of said pins 8 are provided with an axial recess 10 therein to receive the free ends of cooperating guide pins, as will be hereinafter described.

Each of the compartments 7 is arranged immediately below the points where the rails 1 are to be superimposed on the cover, so that the springs 9 may resiliently support the load passing over the rails. The partitions 6 have recesses 11 formed at their upper edges to receive one or more leaf springs 12 insertable therein, said leaf springs carrying pins 13 intermediate their ends to engage in the recesses 10 of the pins 8, said leaf springs 12 supplementing the action of the springs 9 and bearing on the bottom wall of the box 3 and against the cover plate 4. In place of two springs one wide spring may be employed.

In order to secure the cover to the box, said cover and box are provided with reg-

istering bolt holes therein to receive bolts 14 spaced at suitable intervals on the tie. The bolts are preferably flanged as shown, a sleeve 15 in the form of a resilient lock washer being adapted to encircle each of the bolts 14 to abut the box 3 and the head of the bolt, so that all of the bolts, when tightened, will space the cover and box a certain distance. The sleeve 15 also prevents the accidental rotation of the bolt in the hole, because the split ends of said sleeve bite into the material of the bolt and the box to hold said parts against relative rotation. A gasket 16' may be interposed between the cover 4 and the head of the bolt so that when the cover moves upwardly after the load has passed, such movement will be noiseless and prevent jar or injury to the parts. An additional purpose of the gasket 16' is to prevent moisture from working its way into the parts.

It is obvious that when the load passes over the tie, the springs 9 and 12 will permit the moving of the cover toward the box, and that as soon as the load has moved from the tie, said springs will lift the cover from the box to its normal position shown in Figs. 3 and 5.

Clips 16 are used to hold the rail in place on the tie, said clips each having an elongated slot or aperture 17 therethrough to slidably receive a bolt 18 to be inserted into a threaded aperture in the tie. In order to prevent the rails from spreading, said cover has a rib 19 projecting upwardly therefrom at each of the rail receiving points, said ribs being parallel and adapted to bear against the outer side of the rails. The rails will be prevented from moving inwardly toward each other by the flanges of the driving wheels of the train bearing outwardly thereon.

It will be noted that with my improved form of tie the spacing between the rails is constant no matter whether the tie is flexed or not, so that the rails always act together.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a device of the kind described and in combination, a rail tie comprising a hollow box open at the upper side thereof, a cover flanged at its edges to fit said open side and slidably engage the vertical walls of the box, means for securing a rail to said cover, means for yieldably maintaining said cover against seating on the box, and means for adjustably securing said box and cover

together, said last-mentioned means comprising bolts adapted to be inserted through registering apertures of the box cover, and means between said bolts and box to limit the insertion of the bolts thereinto and lock them against accidental rotation.

2. In a device of the kind described and in combination, a rail tie comprising a hollow box open at the upper side thereof, a cover flanged at its edges to fit said open side and slidably engage the vertical walls of the box, means for securing a rail to said cover, means for yieldably maintaining said cover from seating on the box, and means for adjustably and detachably securing said box and cover together, said last-mentioned means comprising bolts adapted to be inserted through registering apertures of the box cover, and spring lock washers encircling said bolts to abut against said box to limit the insertion of the bolts thereinto and locking said bolt and box to prevent accidental relative rotation of the bolts.

3. In a device of the kind described and in combination, a rail tie comprising a hollow box open at the upper side thereof, a cover flanged at its edges to fit over said open side and slidably engage the vertical walls of the box, means for securing a rail on said cover, means for yieldably maintaining said cover from seating on the box, said last-mentioned means comprising coil springs vertically arranged between said box and cover beneath said rail, leaf springs supplementing said coil springs and bearing on said box bottom and cover, and means for detachably securing said cover and box together to permit separation thereof.

4. In a device of the kind described and in combination, a rail tie comprising a hollow box open at the upper side thereof, a cover flanged at its edges to fit over said open side and slidably engage the vertical walls of the box, means for securing a rail on said cover, means for yieldably maintaining said cover from seating on the box, said last-mentioned means comprising pins extending upwardly from the bottom of the box, coil springs encircling said pins and vertically arranged between said box and cover beneath said rail, leaf springs supplementing said coil springs and bearing on said box bottom and cover, pins carried by said leaf springs to project into said coil springs and slidably into said first-mentioned pins, and means for detachably securing said cover and box together to permit separation thereof.

In testimony whereof, I have hereunto signed my name in the presence of two subscribing witnesses.

L. D. SPRATT.
